UNITED STATES PATENT OFFICE.

LEWIS WERTZ, OF OREGON, ILLINOIS.

COMPOUND WATER-WHEEL.

SPECIFICATION forming part of Letters Patent No. 501,123, dated July 11, 1893.

Application filed October 15, 1892. Serial No. 448,955. (No model.)

To all whom it may concern:

Be it known that I, LEWIS WERTZ, a citizen of the United States of America, residing at Oregon, in the county of Ogle and State of Illinois, have invented certain new and useful Improvements in Compound Water-Wheels, of which the following is a specification.

My invention relates to certain improvements in water-wheels, or rather in certain combinations thereof with a view to constructing what I call a compound water-wheel, the purpose of which is to obtain from a given volume and head of water more power than can be obtained from a single wheel.

My invention is illustrated in the drawings by means of two figures, of which—

Figure 1 is a vertical diametrical section of a penstock and three water wheels therein; and Fig. 2 is a horizontal section in line 2—2, of Fig. 1.

In the drawings, the penstock is lettered A, the intake, a , and the discharge, a' . Extending across the interior of the penstock are two spiders, a^2 , a^6 , in which is journaled a shaft, B. The interior of the penstock is also provided with three horizontal internal flanges, a^3 , a^4 , a^5 . Fast upon this shaft are three wheels, C, C', C'', which may be of any preferred form of submerged wheel. The penstock is made up of four sections, a^6 , a^7 , a^8 , a^9 , secured together by means of flanges, a^{10} , a^{11} , a^{12} , so as to make an air-tight casing from top to bottom. The issue, c^2 , of the wheel, C'', is larger than the issue, c' , of the wheel, C', which, in turn, is larger than the issue, c , of the wheel, C.

In operation, the water is let through the

intake, a , and soon fills the entire penstock from top to bottom driving out all the air therefrom, after which it is obvious that the pressure of the water upon the three wheels will be substantially the same for the reason that the water which is below the upper wheel, but still within the air-tight penstock, will draw by suction upon said wheel with the same force that it bears by weight upon the one beneath it. The making of the lower issues, in turn, larger than those above them insures a less obstruction to the water from the lower wheels, and, consequently, gives a better suction upon those above.

I prefer to place these wheels in a vertical line, but it is obvious, of course, that the placing of them upon a horizontal shaft and the shaping of the penstock to make the same possible would not depart from my invention.

I claim as new and desire to secure by Letters Patent—

The combination of an air-tight penstock, a shaft journaled therein, two or more wheels fast upon this shaft and having issues of increasing size one after the other, a series of air-tight partitions separating said wheels and suitable inlets and outlets whereby the water is supplied to the penstock, passed first through the wheel having the smallest issue and then in turn through the wheels having issues of increasing size and finally discharged at the outlet; substantially as described.

LEWIS WERTZ.
